UNITED STATES PATENT OFFICE

RAYMOND W. DULL, OF LA GRANGE, ILLINOIS, ASSIGNEE TO SAFETY MINING COMPANY, OF CHICAGO, ILLINOIS, A CORPORATION

BLASTING CARTRIDGE

Application filed September 16, 1929. Serial No. 392,849.

This invention relates to blasting cartridges of the general type shown in the Ferrell et al. Patent No. 1,610,274, granted December 14, 1926. As shown in the patent, this type of cartridge consists of a substantially cylindrical steel shell having an internal gas chamber, a pressure responsive discharge device associated with one end of the shell and charging and energizing means associated with the other end of the shell. The energizing means is in the form of an electrode which extends thru a wall of the shell and into the gas chamber. The electrode forms one terminal of a circuit including an electrically activated heat producing device, as an intermediate element, and the steel shell, as the other electrode or terminal. The function of the electrode requires that it be reliably insulated from the shell and the fact that it enters the gas chamber requires that it be well packed to prevent leakage of gas and withstand pressure.

Since the advent of the cartridge shown in the above mentioned patent, many improved cartridge structures have been developed and much of this development work has been directed to improvement of the mounting, insulation and packing of the electrode. Notwithstanding these efforts, this portion of the cartridge has continued to be a source of trouble. The difficulties involved can be readily appreciated in view of the fact that the electrode is subjected to whatever pressure exists within the gas chamber and that such pressure approximates 40,000 pounds per square inch at the time of discharge. The effect of this extremely high pressure has been to blow out or, at least, rupture the insulating packing to such an extent as to destroy the gas tight seal between the electrode and shell.

An object of the present invention is to provide a remedy for these defects.

Specifically, it is an object of the invention to provide an insulated and sealed electrode for blasting cartridges of the type indicated, of such construction and design that the ratio of pressure area to pressure resisting area will provide a substantial factor of safety.

The more specific objects of the invention will appear in connection with the following description of the accompanying drawings.

In the drawings,

Figure 1 is a view in side elevation with a portion of the wall broken away to disclose the position of the heater in a cartridge of the type under consideration,

Figure 2 is a view in longitudinal section of a cartridge embodying my invention,

Figure 3 is a view in transverse section, taken along line 3-3 of Figure 2,

Figure 4 is a view in transverse section taken along line 4-4 of Figure 2, and

Figure 5 is a transverse sectional view taken along line 5-5 of Figure 2.

The improvements constituting the present invention are embodied in a cartridge which in general comprises a substantially cylindrical metallic body 1, having an internal gas chamber 2, the open end of which is adapted to be closed and sealed by means of a rupturable disc 3. This disc seats against a shoulder 4 formed on the body and is backed up by a relatively hard steel shear ring 5. The disc and shear ring are held in assembled relation with respect to the cartridge body by means of the tubular portion 6 of a discharge cap 7. The portion 6 is externally threaded and engages corresponding threads formed internally of the discharge end of the cartridge. The discharge cap is provided with an axial gas passage 8 and a plurality of transverse or radially arranged outlet ports 9. The opposite end of the cartridge is provided with an electrode 10 which extends into the gas chamber 2 and which is effectively sealed and insulated with respect to the cartridge body. A valve 11 cooperates with the outer end of the electrode 10 to control the passage of gas therethrough and into the chamber. A terminal cap 12 associated with the extreme end of the cartridge body provides means whereby a source of electricity may be connected to the electrode and metallic cartridge body respectively.

The improvements with which the present invention is chiefly concerned are in connection with what may be termed the charging

end of the cartridge as distinguished from the discharge end thereof. One of the principal features is the construction and mounting of the electrode 10 in the end of the shell body. It might be stated in this connection that the function of the electrode is to make contact with one end of an electrically energizable heater unit 13, the opposite end of which is adapted to contact with some portion of the metallic cartridge body or some element having electrical contact therewith, such, for example, as the rupturable disc 3. The electrode 10 passes through an aperture in the end wall 14 of the gas chamber 2. Inwardly of the wall 14 there is provided a substantially cylindrical pocket 15 and on the opposite side of the wall the shell body is extended in sleeve-like form to provide an internal pocket substantially circular in cross section. A flange 17 is formed on the electrode and this flange is disposed within the cylindrical pocket 15. Insulating members 18 and 19 serve to separate the electrode from the metallic shell body in order to prevent the passage of electricity directly from one to the other. The inner end of the electrode is surrounded by an insulating sleeve 20 which serves to separate the electrode from the surrounding nut 21 which has electrical connection with the cartridge body. The head of nut 21 is of hexagon or other suitable form adapted to receive a socket wrench or the like and the periphery of the nut is provided with screw threads for cooperation with corresponding threads formed internally of the pocket 15. By virtue of this construction, the nut may be adjusted to provide the necessary pressure between the adjacent surfaces of the flange 17, wall 14 and interposed insulating member to provide effective seal against the escape of gas from the chamber 2. This nut, by virtue of its position and relation to the electrode performs an additional and very important function in the cartridge. It will be observed that the entire cross sectional area of the nut is exposed to the interior of the gas chamber, but, by reason of the connection between the nut and the body of the shell, whatever pressure is exerted on the nut is transmitted directly to the shell body and is not imposed upon the electrode and the material employed to insulate the electrode from the body. This arrangement gives rise to the possibility of making the inner end of the electrode of comparatively small cross sectional area as compared with the area of the surfaces of flange 17 and wall 14 which provide the gas tight seal for the electrode. In the specific construction shown, the cross sectional area of the inner end of the electrode which is exposed to the pressure within the gas chamber is substantially equal to, or less than the area of the sealing surfaces and in this relationship lies the

solution to the problem of providing an effective and durable seal for the electrode. If this relationship is not employed, it is practically impossible to find an insulating material capable of withstanding the pressures involved in a cartridge of this character.

An axial passage 23 extends from the outer end of the electrode to a point adjacent the inner end thereof at which point a transverse passage 24 is located to place passage 23 in communication with the interior of the gas chamber. The valve body 25 which carries valve member 11 is screw threaded on the outer end of the electrode and is insulated from the cartridge body by means of an insulating disc 27. A charging port 26 in the valve body communicates with the interior thereof and with the end of passage 23 when the valve member 11 is adjusted out of engagement with the end of the electrode.

The terminal cap 12 is adapted to be detachably connected with the end of the cartridge body by means of suitable lugs and bayonet slots as indicated at 27 and 28. Metallic plug 29 is centrally positioned in the terminal cap and is insulated therefrom by the disc 30 and sleeve 31. A setscrew 32 is provided for the purpose of securing a conductor in the plug. A second conductor may be secured in the terminal cap by means of the aperture 33 and setscrew 34. Electrical contact is established between the plug 29 and the electrode by means of a coil spring 35 having one end engaging the plug and the opposite end engaging the valve body.

For the purpose of rendering the cartridge normally inoperative a short circuiting device is provided for establishing an electrical connection between the electrode and the shell body. This device consists of a sleeve member 36 having an inwardly directed flange 37 which is adapted to cooperate with a plurality of knife edge contacts 39 formed on the under surface of the valve body. A spring 38 is interposed between the flange 37 and the outer surface of the wall 14. This spring tends to normally maintain the flange 37 in engagement with the contacts 39 and since the spring is in electrical contact with the body of the cartridge, a short circuit is provided from the electrode to the body. The sleeve 36 is so designed as to length that it is adapted to be engaged and moved by the end of the terminal cap 12 when the latter is attached to the cartridge, thus breaking the connection between flange 37 and contacts 39.

The extreme inner end of the electrode 10 is provided with external screw threads for engagement with corresponding threads formed internally of a pocket in the end of heater support 41. The heater support is provided with an outwardly tapered opening to facilitate the entering of a heater unit

therein. Slots 43 are provided in the end of the support 41 to receive a suitably formed wrench to be used in assembling the heater support on the electrode.

5 The cartridge hereinabove described is adapted to be charged with a highly compressed or liquefied gas through the valve controlled passage in the electrode. The discharge of the cartridge is effected by connecting the leads from a source of electricity to the electrode and cartridge body respectively, thereby including the heater unit in circuit with a source of electricity. When this circuit is energized, the heater unit gives 10 off a sufficient amount of heat to vaporize the charge within the cartridge and increase pressure thereof to a predetermined point at which the disc 3 is designed to rupture. The rupture of disc 3 permits the escape of 15 the gaseous charge through passage 8 and radial ports 9 of the discharge cap and into the material to be blasted.

Prior to the present invention considerable difficulty has been experienced with a wide 20 variety of structural forms of blasting cartridges, particularly in connection with the insulation and sealing of the electrode. At the time of discharge of a cartridge of this type the pressure within the gas chamber 25 approximates 40,000 pounds per square inch and this extremely high pressure has caused the destruction of the insulating elements between the electrode and cartridge body in many different types of construction. An 30 entirely adequate solution of this difficulty seems to be present in the construction herein described wherein the electrode nut receives much of the pressure which exists within the gas chamber and transmits the same directly 35 to the cartridge rather than to the electrode. It has been found that with such a construction it is possible to maintain a reliable relationship between the area of the electrode 40 which is subjected to pressure and the area 45 of the insulating material which must resist this pressure. Satisfactory results can be secured if the end of the electrode exposed to the pressure in the chamber is equal to or less than the area of the pressure resisting 50 surface, although in order to secure a desirable factor of safety, it is well to provide a substantially greater area for the resisting surface than exists for the surface exposed to the pressure.

55 Claims:

1. In a device of the character described, the combination with a body having a gas chamber, of an electrode projecting thru the body and extending into said chamber, 60 cooperating sealing surfaces on said electrode and body and a material having the combined properties of an insulator and packing interposed between said surfaces, the effective area of said surfaces being substantially equal to or greater than the area

of the electrode which is exposed to the pressure within the chamber.

2. A blasting cartridge comprising a metallic body having an internal gas chamber, an electrode projecting thru an opening in 70 said body and having a portion thereof exposed to the pressure within said chamber, an insulating member interposed between said electrode and the walls of said opening, cooperating sealing surfaces on said electrode 75 and body, an insulating and sealing member interposed between said surfaces, the effective area of the sealing surface on said electrode being substantially equal to or greater than the area of the portion exposed to the 80 pressure within the chamber.

3. A blasting cartridge comprising a metallic body having an internal gas chamber, an electrode projecting thru an opening in 85 said body and having a portion thereof exposed to the pressure within said chamber, cooperating pressure resisting surfaces on said electrode and body, the effective area of said pressure resisting surfaces being at least 90 equal to the area of that surface of the electrode which is exposed to the pressure with- 95 in the chamber.

4. A blasting cartridge comprising a metallic body having an internal gas chamber, said body having a circular opening thru 95 a wall thereof and a cylindrical pocket adjacent said opening on the interior of said body and communicating with said chamber, an electrode positioned in said opening and extending on opposite sides of said wall, a 100 radial flange on said electrode and disposed within said pocket, an insulating and sealing member interposed between the end wall of said pocket and one face of said flange, and means surrounding said electrode and 105 acting against the other face of said flange for effecting the sealed relation, said means serving to prevent access of pressure within the chamber to the inner radial face of said flange.

5. A blasting cartridge comprising a metallic body having an internal gas chamber, said body having a circular opening thru 110 a wall thereof and a cylindrical pocket adjacent said opening on the interior of said body and communicating with said chamber, an electrode positioned in said opening and extending on opposite sides of said wall, an insulating sleeve positioned between said electrode and the wall of said circular opening, a radial flange on said electrode disposed within said pocket, an insulating member interposed between the end wall of said pocket and one radial face of said flange, an insulating sleeve surrounding the inner end 115 of said electrode, a nut surrounding said insulating sleeve, an insulating member interposed between the other radial face of said flange and the adjacent end of said nut, and threads formed on the interior of said pocket 120 125 130

for cooperation with the threads on said nut.

6. A blasting cartridge comprising a substantially cylindrical metallic body having a gas chamber formed therein, a pressure responsive discharge device associated with one end of said body and gas chamber, a transverse wall adjacent the opposite end of said body, said wall having a perforation therethru leading into the chamber, an electrode extending thru said perforation and into the chamber, a radial flange formed intermediate the ends of said electrode, said flange being positioned within the chamber and having a radial surface adapted for cooperation with the inner radial surface of said transverse wall to provide a seal, a nut surrounding the inner end of said electrode and adapted to coact with the other radial face of said flange, said nut having threaded engagement with the interior of said body whereby axial movement of the electrode may be effected, and insulating material interposed between adjacent surfaces of the electrode and the body and nut respectively.

26 Signed at Chicago, Ill., this 13th day of September, 1929.
